UNITED STATES PATENT OFFICE.

ISIDORE GOLDSTEIN, OF NEW YORK, N. Y., ASSIGNOR TO PEKETT HEADWEAR CO., A COPARTNERSHIP COMPOSED OF CHARLES W. PEKOWSKY AND ISIDORE GOLDSTEIN, BOTH OF NEW YORK, N. Y.

DESIGN FOR A HAT.

Application filed October 20, 1924. Serial No. 11,128. Term of patent 3½ years.

To all whom it may concern:

Be it known that I, ISIDORE GOLDSTEIN, a citizen of the United States, residing at New York, county of New York, State of New York (whose post-office address is 826 Broadway, city and State aforesaid), have invented a new, original, and ornamental Design for Hat, of which the following is a specification, reference being had to the accompanying drawing, forming a part thereof.

I claim:—

The ornamental design for a hat, as shown.

ISIDORE GOLDSTEIN.
